Primary Examiner—Stella M Reid*Assistant Examiner*—Elizabeth J Oswecki(74) *Attorney, Agent, or Firm*—Birch, Stewart, Kolasch & Birch, LLP(57) **CLAIM**

The ornamental design for a bottle, as shown and described.

DESCRIPTIONFIG. 1 is a front view of the bottle showing my new design;
FIG. 2 is a left side view thereof;

FIG. 3 is a rear view thereof;

FIG. 4 is right side view thereof;

FIG. 5 is a top plan view thereof; and,

FIG. 6 is a bottom plan view thereof.

FIGS. 1-4 are shown broken away to indicate indeterminate length.

The broken line showing of the remainder of the bottle is for environmental purposes only and forms no part of the claimed design.
